United States Patent Office

Des. 195,461
Patented June 18, 1963

195,461

SHAVER

Raymond T. Cassidy, 45 Federal St.,
Stratford Town, Conn.

Filed Feb. 5, 1962, Ser. No. 68,666

Term of patent 14 years

(Cl. D22—3)

FIG. 2

FIG. 4

FIG. 1

FIG. 5

FIG. 3

FIG. 1 is a front elevation of a shaver showing my new design, the side opposite thereto being similar in appearance;

FIG. 2 is a top view thereof;

FIG. 3 is a bottom view thereof;

FIG. 4 is a side elevation as seen from the left of FIG. 1; and

FIG. 5 is a side elevation as seen from the right side of FIG. 1.

The essential features of the design reside in the portions shown in solid lines on the drawing.

I claim:

The ornamental design for a shaver, substantially as shown and described.
